UNITED STATES PATENT OFFICE.

WILLIAM L. TULL, OF GRIDLEY, CALIFORNIA, ASSIGNOR OF ONE-HALF TO ALBERT A. WHITNEY, OF STOCKTON, CALIFORNIA.

ADJUSTABLE FRUIT-JAR HOLDER.

1,171,370.

Specification of Letters Patent.

Patented Feb. 8, 1916.

Application filed July 23, 1914. Serial No. 852,608.

To all whom it may concern:

Be it known that I, WILLIAM L. TULL, a citizen of the United States, residing at Gridley, in the county of Butte, State of California, have invented certain new and useful Improvements in Adjustable Fruit-Jar Holders; and I do declare the following to be a clear, full, and exact description of the same, such as will enable others skilled in the art to which it appertains to make and use the same, reference being had to the accompanying drawings, and to the characters of reference marked thereon, which form a part of this application.

This invention relates to improvements in fruit jar holders and by using said device all necessity of touching the jar with the hands is eliminated, thereby reducing the danger of burning the hands and at the same time a means is provided for holding the jar against turning when the cover is being screwed thereon or unscrewed therefrom.

A further object of the invention is to produce a simple and inexpensive device and yet one which will be exceedingly effective for the purposes for which it is designed.

These objects, I accomplish by means of such structure and relative arrangement of the parts as will fully appear by a perusal of the following specification and claims.

On the drawings, similar characters of reference indicate corresponding parts in the several views.

Figure 1 is a perspective view of the holder. Fig. 2 is a side view from the outside showing the hinge bent inwardly. Fig. 3 is a top plan view of the device as it would appear in folded position.

Referring now more particularly to the characters of reference on the drawings, I first provide two handle members each comprising an outer portion 1 and an inner portion 3 at an angle thereto, such inner portions 3 being provided with keepers 2 of metal covered with a lamination of rubber, leather or other adhesive material 13. The ends 3, projecting through these keepers 2, are hinged to suitable metallic links 6 which, at their other ends as at 8, are hinged to links 7 made of bent wires, as shown, which are covered with rubber tubing or similar material 12. The said links 7, at their free

ends, are hinged together by means of a 55 collar 10.

Projecting downwardly from the keepers 2 are finger members 4 having inwardly projecting ends 5. In practice, the jar or other member to be held is inserted within the circumference of the holder and rests against the points 5 which prevent the holder from slipping upwardly on the jar or other member. By gripping the handles 2 and moving them toward each other, the holder is engaged in frictional contact with the jar or other member, all for the purposes set out in the preamble to this specification.

When the device is fully extended, as shown in Fig. 1, it will fit around one size of jar. To fit a smaller jar, one of the links 6 is folded inwardly to reduce the circumference of the holder, whereupon a smaller sized jar can be engaged by the holder, the frictional engagement of the holder with the jar preventing the link 6 from unfolding again. When a still smaller jar is to be used, the other of the links 6 is folded inwardly to further reduce the circumference of the holder with an apparent function. (See Fig. 3.) The covered keepers 2 afford a good gripping surface and this function is aided further by means of the tubing 12.

From the foregoing description it will readily be seen that I have produced such a device as substantially fulfills the objects of the invention as set forth herein.

While this specification sets forth in detail the present and preferred construction of the device, still in practice, such deviations from such detail may be resorted to as do not form a departure from the spirit of the invention as defined by the appended claims.

Having thus described my invention what I claim as new and useful and desire to secure by Letters Patent is:—

1. A holder of the character described comprising two handle members, each handle member having an outer portion and an inner portion at an angle thereto, the latter being adapted to partially surround a jar or the like, a link connected with each of said inner portions, another link hinged to each of said first named links, said last named links being hinged together, said first named links being adapted to fold inwardly

to decrease the diameter of the holder, as described.

2. A holder of the character described comprising two handle members, each handle member comprising an outer portion and an inner portion at an angle thereto, the latter being adapted to partially surround a jar or the like, a link connected with each inner portion, another link hinged to each of said first named links, a collar disposed around and joining the opposite ends

of said last named links, said first named links being adapted to fold inwardly to decrease the diameter of the holder, as described.

In testimony whereof I affix my signature in presence of two witnesses.

WILLIAM L. TULL.
